[57] CLAIM

The ornamental design for a baseball cap carrying case, as shown and described.

DESCRIPTION

FIG. 1 is a perspective view of a baseball cap carrying case showing my new design;

FIG. 2 is a left side elevational view thereof; the right side elevational view being a mirror image thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is an exploded perspective view thereof; and,

FIG. 8 is an enlarged scale fragmentary sectional view taken along line 8—8 of FIG. 7, showing a connection of lid and container and shown in a closed position for clarity of illustration.
